UNITED STATES PATENT OFFICE.

FRED BUTCHER, OF ST. LOUIS, MISSOURI, ASSIGNOR TO THE INVENTORS' MANUFACTURING ASSOCIATION, OF SAME PLACE.

DESIGN FOR A BASE FOR HYDROCARBON-BURNERS.

SPECIFICATION forming part of Design No. 31,834, dated November 14, 1899.

Application filed July 31, 1899. Serial No. 726,699. Term of patent 31 years.

To all whom it may concern:

Be it known that I, FRED BUTCHER, a citizen of the United States, residing in the city of St. Louis, State of Missouri, have invented 5 a new and useful Design for a Base for a Hydrocarbon-Burner, of which the following is a specification.

Figure 1 is a side elevation of a burner embodying my new design, the view being taken 10 looking in the direction indicated by the arrow I in Fig. 2. Fig. 2 is a top plan view taken looking in the direction indicated by the arrow II in Fig. 1. Fig. 3 is a bottom plan view taken looking in the direction indicated by the arrow III in Fig. 1.

As shown in the drawings, the leading or 15 essential feature of my new design for a base for a hydrocarbon-burner consists of the horizontal plate 1, having an opening at its center, the hollow cylinder 2 extending upwardly

from the center of said plate 1, the three blocks 4 extending upwardly from the rim of the plate 1, the hollow cylinder 8 extending downwardly from the center of the plate 1, the openings through the plate 1, the cylinder 2, and the cylinder 8 being in vertical alinement, the hollow cylinder 9 extending downwardly from near the rim of the plate 1, the hollow cylinder 14 extending downwardly from the plate 1, and the rib 15 extending 25 from the cylinder 9 to the cylinder 14 along the lower face of the plate 1.

I claim—

The design for a base for a hydrocarbon-burner, substantially as herein shown and described. 30

FRED BUTCHER.
